UNITED STATES PATENT OFFICE.

CLEMENT L. HUGHES, OF LEWISTOWN, ILLINOIS, ASSIGNOR OF ONE-HALF TO L. I. LACKY, OF LEWISTOWN, ILLINOIS.

CIGAR-VENDING MACHINE.

1,120,500.

Specification of Letters Patent.

Patented Dec. 8, 1914.

Application filed February 3, 1914. Serial No. 816,259.

To all whom it may concern:

Be it known that I, CLEMENT L. HUGHES, a citizen of the United States, residing at Lewistown, in the county of Fulton and 5 State of Illinois, have invented certain new and useful Improvements in Cigar-Vending Machines; and I do declare the following to be a full, clear, and exact description of the invention, such as will enable others skilled 10 in the art to which it appertains to make and use the same.

This invention relates to merchandise delivery cabinets or vending machines and more particularly to improvements in cigar 15 vending machines.

The object of the invention is to provide a simple, practical and inexpensive machine of this character which will deliver the cigars one at a time without injury to them and which will permit the delivery of the 20 cigars from the original container or cigar box bearing the internal revenue stamp, the latter being exposed to view and being kept intact until the box is emptied.

With the above and other objects in view, the invention consists of certain novel features of construction, combination and arrangement of parts as will be more fully described and claimed.

In the accompanying drawings:—Figure 1 is a vertical front rear sectional view through a cigar vending machine embodying my invention; Fig. 2 is a top plan view, the cigar box retaining frame being removed; Fig. 3 is a perspective view of the cigar box retaining frame; Fig. 4 is a sectional perspective view showing one half of the cigar feeding reel; and Fig. 5 is a detail sectional view taken on the line 5—5 of Fig. 2.

Referring more particularly to the drawings, 1 denotes a suitable casing preferably but not necessarily made of rectangular form and of metal, its upper portion forming a hopper 2 for the cigars C which feed into the same by gravity from the original container or cigar box B. The cigars in the hopper 2 are exposed to view through a glass or other transparent top 3 including a cross bar 4 arranged at the rear of the casing. The bottom of the hopper 2 is formed by downwardly and inwardly inclined feed

plates 5, 6 and two spaced semi-cylindrical plates 7, the outer ends of which have flanges 8 suitably secured to the side walls 55 of the casing 1. The inner ends of the semi-cylindrical plates 7 are spaced apart to form a slit 9 through which works the radiating arms 10 of a spider 11 which latter has its hub fixed centrally on a transverse shaft 13 60 journaled in bearings in the side walls of the casing. The spider 11 is preferably cast in one piece and suitably secured to the ends of its radiating arms 10 are blades 14 arranged in an angular row so that they will 65 travel over the curved upper faces of the plates 7 and form in conjunction with the latter pockets of sufficient size to receive a single cigar. As this rotary feeding member or reel composed of the spider with its 70 blades 14 rotates in the direction of the arrow in Fig. 1, it will pick up the cigars from the rear inclined plate 6 and feed them over the curved plates 7 and under the front plate 5 which latter has formed on its inner 75 edge an arc shaped guiding flange 15 which is concentric with the axis of the shaft 13 as are also the curved plates 7, see Fig. 1. The lower edge of the guide 15 terminates above the lower edges of the plates 7 so that the 80 cigars will be deposited on a downwardly forwardly inclined chute 16 arranged opposite a discharge opening in the front wall of the casing so that the cigars will be deposited on a delivery cup 17 from which they may 85 be readily removed.

The upper rear edge of the casing 1 is left open for the reception of the cigar box B the end of which latter is removed so that the cigars may feed by gravity to the plate 90 6. The box is fastened in its downwardly and forwardly inclined position shown in Fig. 1 by a skeleton frame 18 shown more clearly in Fig. 3 and composed of four angle metal side bars 19 united by front cross bars 95 20—21 and rear angle metal cross bars 22. The bars 19 are also united by angle metal corner bars 23 and connecting bars 24 so that this skeleton frame surrounds the box B and has one end open to permit the box 100 to be slid into it. When the box is in position it will be noted that all parts of its exterior sides and ends will be exposed so that the internal revenue stamp, the Gov-

ernment inspector's notice, the maker's name, etc., will be exposed to view.

The skeleton frame 18 is detachably mounted in the opening in the casing by forming on the inner edge of the cross bar 21 a longitudinally extending curved or hook shaped lip 25 adapted to enter a slot 26 formed in an upwardly and rearwardly inclined longitudinally extending flange 27 formed on the upper edge of the rear wall of the casing. The cross bar 20 is fastened to the upper angle bars 19 slightly inward of their front ends which latter enter under the cross bar 4 so that the front edge of the bar 20 bears against the bar 4 when the frame is in position. A suitable fastening, preferably a clasp is arranged on the bars 4, 20 and as shown the eye or staple member 28 is fastened to the center of the bar 20 while the clasp 29 is fastened to the center of the bar 4. A padlock 30 is employed as shown to retain the frame 18 and hence the box B in position so that unauthorized persons cannot disturb the same. In order to prevent the box B from slipping downwardly in the frame angle metal stops 31 are provided on the inner faces of the side walls and against which the edges of the open end of the box B rest, see Figs. 1 and 2.

30 The shaft 13 may be operated in any desired manner but I preferably employ a suitable ratchet mechanism for intermittently moving the shaft step by step to rotate the feeding reel so that one cigar is delivered at a time. This operating mechanism is arranged in a suitable casing 32 formed or secured to one side wall of the casing 1 and to permit access to the mechanism a slideable cover 33 covers the side of the casing 32 and is fastened in position by a suitable lock 34, see Fig. 2. An operating lever for this feed mechanism is shown at 35 and works through a longitudinal slot 36 formed in the top of the casing 32 and arranged adjacent a coin receiving slot 37.

The operating mechanism is of course normally locked and is released by the proper coin when deposited in the slot 37 as is common with vending machines. The coins after serving their purpose, drop into the bottom of the casing 32 which latter is in communication with the bottom of the main casing 1 through an opening 38 shown in Fig. 1, so that the coins accumulating in the former casing may pass over into the latter which is more spacious. The money is removed from time to time by removing the padlock 32 and sliding the cover 33 longitudinally in a forward direction a suitable handle 39 being provided for this purpose.

From the foregoing it will be noted that by constructing the casing and the box supporting frame or cage as set forth, the original container or cigar box will be effectively

supported so that its exterior will be exposed to view and its seals, stamps or other identifying marks may be left intact while the cigars will be passed freely from the box into the hopper where they are exposed to the view of the purchaser. In the hopper 70 they will be separated and fed individually to the delivery cup without injury to them and with regularity. It will be further noted that the vending or delivery mechanism is simple in construction and hence 75 may be produced at a small cost and it has been found practical and effective in operation.

Having thus described my invention, what I claim as new is:—

1. A machine of the character set forth comprising a casing having in its upper portion a hopper including an inclined feed plate and stationary, longitudinally spaced arc shaped plates, a shaft journaled concentric with said arc shaped plates, a spider fixed to the shaft and projecting through the space between said plates, blades fixed centrally to the outer ends of said arms and adapted to pass around said plates and 90 means for receiving the merchandise discharged from the hopper by the fastening blades.

2. A machine of the character set forth comprising a casing having in its upper portion a hopper including an inclined feed plate and stationary, longitudinally spaced arc shaped plates, a shaft journaled concentric with said arc shaped plates, a spider fixed to the shaft and projecting through the space between said plates, blades fixed to the outer ends of said arms and adapted to pass around said plates, a second inclined plate inclined in the opposite direction to the first mentioned inclined plate and having a curved depending guide flange spaced from said arc shaped plates and concentric with the axis of the shaft, a downwardly inclined chute spaced below said curved flange, a delivery cup on the exterior of the casing 110 and arranged below said chute, both chute and cup being opposite and opening in the casing, and means for detachably securing to the upper portion of the casing, a merchandise container to discharge merchandise 115 upon the first mentioned inclined plate.

3. A machine of the character described comprising a casing having a merchandise container receiving opening, a merchandise delivery mechanism in the casing, a slotted flange on the lower edge of said opening, a skeleton frame to receive an open end merchandise container and composed of angle metal side bars connected at its open end by upper and lower cross bars, the upper cross bar being spaced from the extremities of the side bars to permit said extremities to engage under the upper edge of the opening

in the casing, a depending lip upon the lower cross bar to enter the slot in said flange, a fastening device connecting the upper cross bar with the top of the casing, and 5 stops carried by the casing to engage the open end of the merchandise container when the latter is in the skeleton frame.

In testimony whereof I have hereunto set my hand in presence of two subscribing witnesses.

CLEMENT L. HUGHES.
